Edwin Ford & Basil Browning Inv.

Letters Patent

The Vehicle referred to in these Letters Patent and making part of the same, containing a description in the words of the said Edwin Ford & Basil Browning Inv. themselves of their improvement in preserving flour for exportation and for domestic use,

The barrel is first to be prepared by saturating the inside of it with a strong solution of salt, or salt and alum, five parts of salt and one of alum, made boiling hot - and when perfectly dry, the flour to be packed up in it with one pound of salt to the barrel mixed, through it, common salt or alum salt in preference.
